O. F. McENANEY

PIPE ATTACHMENT FOR STEAM ON KNITTING MACHINES

Filed Dec. 13, 1923

Inventor

Owen F. McEnaney

By Lester L. Sargent.

Attorney

UNITED STATES PATENT OFFICE.

OWEN F. McENANEY, OF BROOKLYN, NEW YORK.

PIPE ATTACHMENT FOR STEAM ON KNITTING MACHINES.

Application filed December 13, 1923. Serial No. 680,415.

To all whom it may concern:

Be it known that I, OWEN F. McENANEY, a citizen of the United States, residing at Brooklyn, in the county of Kings and State of New York, have invented a new and useful Improvement in a Pipe Attachment for Steam on Knitting Machines, of which the following is a specification.

The object of my invention is to provide improved means for moistening artificial fiber silk before it is knitted into cloth by steam on knitting machines, whereby a finer fabric can be produced and the machines can be run faster and more production obtained, and particularly to improve upon my former Patent No. 1,460,972.

I attain the objects of my invention by the mechanism illustrated in the accompanying drawings, in which:

20 Figure 1 is a side elevation of same;
Fig. 2 is a vertical section through same;

and
Fig. 3 is a horizontal section on line 3—3 of Fig. 1.

25 Like numerals indicate like parts in each of the several views.

Referring to the accompanying drawings, I provide a moistening device consisting of a narrow cylindrical wall 9 and a spaced inner cylindrical wall 10 with cap members 11 at the top and bottom of these walls, forming a closed annular chamber 12 into which steam is supplied through the inlet 13 from the steam supply pipe 7 which supports the device and through which steam is supplied from suitable steam pipes suitably arranged on the knitting machine. The inner annular wall 10 is provided with openings 15 through which the steam is admitted

30 to the central chamber 16 from which it flows upward and moistens the thread 5 which is aligned with but spaced above the central chamber 16. I provide a horizontal support 20 by means of which the cylindrical thread guide chamber 21 is affixed to the moistening device wall 9. The thread guide chamber 21 is provided with guide plug 22 of suitable material, such as porcelain, at each end, these plugs having

35 thread channels 23 extending through them, as shown in Fig. 2. I provide an angular arm 24 affixed to the outer wall 9 of the moistening device and disposed opposite thread guide chamber 21 and offset from the

40 moistening device and carrying the thread guide 25 of suitable material, such as porce-

lain, this thread guide member having a thread guide channel 26 extending through it, as shown in Fig. 2. I provide a drain spout 19 opening out of steam chamber 12 to drain off the water condensed from the steam.

In use, the threaded steam inlet 13 of the thread moistening device is screwed onto the end of the steam supply pipe 7 at suitable parts of the knitting machine and steam flows into the chamber 12 and thence through openings 15 into central chamber 16 and thence upward, as indicated by the arrows in Figs. 1 and 2 onto the thread 5 moistening it as it is drawn past the moistening device from the thread guide 22 to the thread guide 25.

Any suitable number of the moistening devices are arranged around the main frame of the knitting machine and threads are fed from the bobbins through suitable wire guides to the thread guides 21. The steam flowing onto the threads 5 from the chamber 16 as the thread continuously travels past that member as it is being knitted, results in a moistening of the threads which has the effect of improving the quality of the fabric knitted and makes it possible to run the machines faster and therefore to get a greater production. The water escaping from spout 19 and from the lower end of chamber 16 is carried off in any suitable manner, as by suitable gutters, functioning in a manner similar to funnels and pipes disclosed in my Patent No. 1,460,972.

What I claim is:

1. In an attachment for steam on knitting machines, a thread moistening device consisting of a cylindrical wall, an inlet opening into said wall for the admission of steam, an inner cylindrical wall having openings admitting steam to the central chamber, cap members enclosing the ends of the chamber between the two cylindrical walls, a plurality of means spaced from but supported by the said moistening device for guiding the thread to be moistened in a path directly over the central chamber from which the steam rises.

2. In a device of the class described, the combination with means for supplying steam to a moistening device, of a moistening device consisting of spaced cylindrical walls having cap members closing the ends to form a closed annular chamber, a steam inlet member opening into said chamber

and adapted to be attached to the steam supply means, a drain opening out of said chamber, means for allowing the steam to escape from the said annular chamber into an open central chamber, a cylindrical thread guiding chamber attached to and supported in spaced relation to the moistening device, said thread guide chamber having suitable thread guiding elements mounted in

the ends thereof, and a second thread guiding element of similar material supported from the moistening device and in opposite relation thereto, said member being aligned with the first mentioned thread guiding member and positioned to guide the thread through the path of the escaping steam from the moistening device.

OWEN F. McENANEY.
